US00D837232S

(12) **United States Design Patent** (10) Patent No.: **US D837,232 S**
 Mariet et al. (45) Date of Patent: ** Jan. 1, 2019

(54) **DISPLAY SCREEN OR A PORTION THEREOF WITH GRAPHICAL USER INTERFACE**

(71) Applicant: **Waymo LLC**, Mountain View, CA (US)

(72) Inventors: **Robertus Christianus Elisabeth Mariet**, Sunnyvale, CA (US); **Brian Douglas Cullinane**, Palo Alto, CA (US); **Manuel Christian Clement**, Felton, CA (US)

(73) Assignee: **Waymo LLC**, Mountain View, CA (US)

(**) Term: **15 Years**

(21) Appl. No.: **29/591,092**

(22) Filed: **Jan. 17, 2017**

Related U.S. Application Data

(60) Continuation-in-part of application No. 29/566,899, filed on Jun. 3, 2016, now Pat. No. Des. 780,197, which is a division of application No. 29/537,499, filed on Aug. 26, 2015, now Pat. No. Des. 761,295, which is a division of application No. 29/438,558, filed on Nov. 30, 2012, now Pat. No. Des. 746,836.

CLAIM

The ornamental design for a display screen or a portion thereof with graphical user interface, as shown and described.

DESCRIPTION

The FIGURE is a front view of a display screen or portion thereof with graphical user interface according to our design. The broken line showings of portions of a display screen, text, and other features in the figures are environmental only and form no part of the claimed design.

1 Claim, 1 Drawing Sheet
